UNITED STATES PATENT OFFICE.

ALONZO B. SPRAGUE, OF BROOKLYN, NEW YORK, ASSIGNOR OF TWO-THIRDS TO RELIEF SOCIETY FOR THE AGED, A CORPORATION OF NEW YORK.

BED AND SPRING THEREFOR.

Application filed November 30, 1925. Serial No. 72,247.

This invention relates to improvements in beds and springs therefor, and has for its primary object, the provision of a bed frame construction which may be adjusted 5 lengthwise for comfortably accommodating persons of various heights, and in which the springs may be lengthwise adjusted to span the bed frame within the limit of its adjustment. It will be appreciated that by 10 constructing a bed of this nature, it is possible to utilize waste space which is usually taken up by beds of a length in excess to that required by a user.

Another object of the invention resides in 15 an adjustable bed and spring which may be quickly collapsed when not in use, and packed in a manner as to require but little space for storing and shipping purposes.

A further object is to provide a combined 20 bed and spring which is simple in construction, cheap of manufacture and highly sanitary when in use.

With these and other objects in view, the 25 invention resides in certain novel construction and combination and arrangement of parts, the essential features of which are hereinafter fully described, are particularly pointed out in the appended claims, and are 30 illustrated in the accompanying drawing, in which:—

Figure 1 is a perspective view of my improved bed and spring.

Figure 2 is a detail sectional view on the line 2—2 of Figure 1.

Figure 3 is a similar view on the line 3—3 of Figure 1.

Figure 4 is a transverse sectional view on the line 4—4 of Figure 3.

Referring more particularly to the drawing, the reference numeral 10 designates my 40 improved bed in its entirety and which includes a bed frame 11 and springs 12.

The bed frame 11 comprises a head frame 13 and a foot frame 14 which are adjustable 45 lengthwise with respect to each other in a manner and for a purpose to be presently described. Both the head and the foot frames are constructed of tubular material such as metal pipe and includes standard fittings for removably connecting the parts together.

The head frame 13 comprises the usual 50 corner posts or vertical tubular legs 15 which support oppositely disposed pipe fittings 16 having angularly disposed branches 17 and

18. The branches 17 receive the threaded ends of a transverse brace rod 19, while the branches 18 threadedly receive one end of the longitudinal tubular side bars 21.

The foot frame 14 comprises corner posts or vertical legs 22 which support pipe fittings 23 having internally threaded branches 24 and 25 which are angularly disposed and similar to the fittings 17 on the head frame, and which are disposed in horizontal alignment with the fittings on said head frame. A tubular brace bar 26 has its ends threaded into the branches 24 of the fittings 23, while branches 25 respectively receive one of the threaded ends of a pair of side bars 27 which are externally threaded as at 28. The side bars 27 are slidable within the tubular side bars 21 and are limited in their inward sliding movement by adjustable thumb nuts 29 which co-act with the threads 28 on the bars 27 and along which bars the thumb nuts are adjustable for obtaining the desired length of the bed. The thumb nuts act in the capacity of stops and engage the free ends of the tubular side bars 21.

The spring 12 comprises a section 30 similar to an ordinary bed spring and which is constructed of a plurality of flexibly connected links extending longitudinally and transversely of the bed frame. One end of the section 30 is suspended from the brace bar 19 by contractile springs 31 and a transversely disposed spring 32 is connected with the end links and has its ends provided with rings which encircle the side bars 21. The head end of the spring is permanently connected with the head frame but the foot end is detachably connected with the foot frame in a manner now to be described.

Rotatably mounted upon the foot brace bar 26 is a roller 33 formed of a pair of tubular lengths of pipe and connected adjacent the meeting ends by a coupling 34. The lengths of pipe and the coupling constitute the roller and move as a single unit. The roller is provided with outwardly extending pins 35 which receive one of the links of the respective chains 36 which are detachably connected with the foot end of the spring section by snap hooks or the like 37. When the bed has been adjusted to the desired length, the spring section 30 is pulled taut and the chain engaged with the respective pins 35 on the roller. To make this spring section more taut, a removable handle mem- 110

ber 38 is carried by the coupling 34 and is adapted to be gripped by the hand of an operator to rotate the roller in a direction to take up any slack in the spring section.

- 5 When the spring has been made sufficiently taut, a removable pin 39 is passed through an opening 40 in the coupling 34 and through an aligning opening 41 in the foot-brace rod 26. This will hold the spring taut 10 until the pin is removed and will also retain the head and foot frame in their adjusted position as the thumb nuts 29 abut the ends of the tubular side bars 21. The handle member 38 is threadedly connected with the 15 coupling 34 and may be removed after the desired adjustment has been obtained, and for sanitary purposes a plug 42 is provided and may be threaded into the recess in the coupling to prevent dirt and insects from 20 collecting therein. The plug is suspended from the foot rest by a flexible chain whereby it is always accessible for use.

When not in use, the tension on the spring may be slackened by unwinding the roller 23 and disengaging the chains 36 from the pins 35. Owing to the flexibility of the spring section 30, the same may be lifted back over the head frame. The foot frame may now be withdrawn from engagement 25 with the head frame after which the side bars 27 are unscrewed from the fittings 23, and the side bars 21 are similarly removed from the fittings 17. The head frame 13 and the foot frame 14 may be brought to lie 30 against each other while the side bars 21 and 27 are adapted to be tied together into a single packages. When collapsed the entire structure may be conveniently packed for storing and shipping purposes.

- 35 40 From the foregoing description it will be seen that after the bed has been adjusted to comfortably accommodate the user, the same gives the appearance of an ordinary bed; but should it be required to lengthen 45 or shorten the bed, it is only necessary to rotate the thumb nut and operate the tension roller.

While I have described what I deem to be the most desirable embodiment of my invention, it is obvious that many of the details may be varied without in any way departing from the spirit of my invention, and I therefore do not limit myself to the exact details of construction herein set forth nor 50 to anything less than the whole of my invention limited only by the appended claims.

What is claimed as new is:—

1. A bed comprising a head frame section having removable tubular side bars, a foot frame section having removable side 60 bars slideable within said tubular side bars, and a brace bar, adjustable stops carried by the side bars of said foot frame section for abutment against the ends of said tubular side bars for limiting the sliding movement 65 of the same in one direction, a spring permanently attached at one end to said head frame section and adapted to be thrown over said section when the same is collapsed, and tension means on the foot frame section 70 for engagement with the other end of said spring for holding said spring in a taut condition between said frame sections, said tension means including a hollow roller journaled for rotation on said brace bar, said 75 roller having an opening therein for register with any one of a plurality of sockets provided in said brace bar, and a removable locking pin passing through said opening and into the registering socket for locking said roller against the tension of said spring. 80

2. A bed comprising a head frame section having side bars and a brace bar, a foot frame section having side bars and a brace 85 bar, the side bars of one frame section being telescopically arranged with respect to the side bars of the other frame section, adjustable stops carried by the side bars of one 90 frame section for engagement with the side bars of the other frame section for limiting the telescopic movement of said side bars with respect to each other in one direction, a spring having one of its ends fixedly mounted to one of said brace bars, and tension 95 means on the other frame sections for engagement with the other end of said spring for holding said spring in a taut condition between said frame sections, said tension means including a hollow roller journaled for rotation in the other of said brace bars, said roller having an opening therein for register with any one of a plurality of sockets provided in said last mentioned brace bar, and a removable locking pin passing through said opening and into the registering socket for locking said roller against the tension of said spring. 100

105 In testimony whereof I have affixed my signature.

ALONZO B. SPRAGUE.
